CLAIM

The ornamental design for a shoe heel and toe guard, as shown and described.

DESCRIPTION

FIG. 1 is a right side elevational view of a shoe heel and toe guard, showing my new design;

FIG. 2 is a left side elevational view thereof;

FIG. 3 is a rear elevational view thereof;

FIG. 4 is a front elevational view thereof; and,

FIG. 5 is a top plan view thereof.

The broken line showing of the remainder of a shoe in FIGS. 1-5 is for illustrative purposes only and forms no part of claimed design.
